UNITED STATES PATENT OFFICE.

FRANCIS W. GIBSON, OF WEST ROXBURY, MASSACHUSETTS, ASSIGNOR TO THE H. D. BEACH COMPANY, OF COSHOCOTON, OHIO, A CORPORATION OF OHIO.

DISPLAY CONTAINER FOR BREAD AND THE LIKE.

Application filed August 29, 1923. Serial No. 660,036.

This invention relates to display stands, and particularly to a stand or rack adapted to be placed upon a counter or other support and from which such articles as loaves 5 of bread, for example, may be conveniently dispensed.

The object of my invention is to provide a simple and inexpensive device of the character indicated which will permit convenient 10 display and ready access to the articles; will be capable of convenient shipment in compact form and subsequent ready assembly; and will provide a maximum display surface for advertising matter descriptive 15 of the goods.

This object is secured in the display stand of the present invention. The construction and manner of assembling my display stand is described and illustrated in the accompanying 20 specification and drawings and the characteristic features of novelty are particularly pointed out in the appended claims. Throughout the specification and claims like reference characters are correspondingly 25 employed and in the drawings:

Fig. 1 is a front elevation of a display stand in accordance with my invention.

Fig. 2 is an end elevation thereof.

Fig. 3 is a plan view.

Fig. 4 is a transverse section and indicating in dotted lines the matter of bending down one of the advertising display panels.

Fig. 5 is a development of one of the end upright blanks of the stand, and

Fig. 6 is a development of one of the shelf forming blanks.

My display stand consists of a pair of end uprights 1 which have the shape best shown in Figs. 2 and 5, and are each preferably 40 formed from a blank of sheet material. The lower edge of each blank is inturned to provide a horizontal supporting foot 2. Above the foot 2 the opposite edges of the blank are bent back upon themselves as indicated 45 at 3 to provide smooth, finished edges. Beyond the flanges 3 the edges of the blank are bent inwardly at substantially right angles to provide attaching flanges 4 to which the bottom and rear members 5 and 6, respectively, of the shelf are bolted or otherwise secured as indicated at 7. Beyond the attaching flanges 4 the edges of the blank are turned back upon themselves as indicated 50 at 8 to provide smooth finished edges.

The shelf or article supporting member of 55 the stand consists of the pair of shelf sections 5 and 6 which are disposed at substantially right angles to each other to define with the end uprights a trough-like containing space. Each shelf section is preferably formed from a blank of sheet material having portions of its end edges bent downwardly at substantially right angles to provide attaching flanges 9, Figs. 4 and 6, which are bolted to the end uprights 1 as indicated 60 at 10. The inner edges of the shelf blanks 5 and 6, considering said blanks as they appear in Fig. 4, are bent downwardly as indicated at 11, Figs. 4 and 6, to provide continuous bearing edges which rest upon the 70 flanges 2 of the end uprights.

Preferably the shelf sections are so mounted upon the end uprights as to leave a space between their opposing edges 11 as indicated at 12, Fig. 4, and said space permits 75 any crumbs or the like which may lodge upon the shelf to be swept therethrough.

One or both of the shelf blanks may be longitudinally weakened in its upper area, as indicated by the scored line 13 in Fig. 6, so that the blank may be bent over upon itself to provide a down turned panel 14, the bounding edges of which are preferably inturned as indicated at 15 to provide a finished edge. The panels 14 may be disposed in any desired angular relation to their shelf sections, whereby to most effectively display advertising matter descriptive 80 of the goods being vended, as indicated in dotted lines, Fig. 4.

When the stand is knocked down for shipment as a flat compact package, the panels 14 are preferably bent to lie in the plane of the shelf sections themselves.

In assembling my stand the shelf sections are bolted to the end uprights by means of the respective attaching flanges 4 and 9 and the bolts 7 and 10 whereby to rigidly connect the uprights and the advertising display panels 14 bent downwardly to the desired angle. When collapsed for shipment, the shelf sections 5 and 6 and the upright sections 1 fit closely upon one another.

Various modifications in the form and construction of my device may obviously be resorted to without departing from the spirit of my invention if within the limits of the appended claims.

What I therefore claim and desire to secure by Letters Patent is:

1. A display stand comprising a pair of spaced end uprights having inturned flanges 5 at their lower edges providing supporting feet, and having inturned attaching flanges disposed above and at an angle to said feet, and a shelf disposed between and rigidly connecting said uprights and consisting of a 10 pair of shelf members disposed at substantially right angles to each other and each fastened adjacent one longitudinal edge to said attaching flanges of the uprights, and said shelf sections having down turned attaching flanges at their ends adapted to be fastened to said uprights adjacent said supporting feet thereof, the inner edges of said members being bent downwardly to rest upon said supporting feet of the uprights and being spaced from each other to provide a discharge opening.
2. A display stand comprising a pair of spaced end uprights having inturned flanges at their lower edges providing supporting 25 feet, and having inturned attaching flanges disposed above and at an angle to said feet, and a shelf disposed between and rigidly connecting said uprights and consisting of a pair of shelf members disposed at substan-

tially right angles to each other and each 30 fastened adjacent one longitudinal edge to said attaching flanges of the uprights, and said shelf sections having down turned attaching flanges at their ends adapted to be fastened to said uprights adjacent said supporting feet thereof, the inner edges of said members being bent downwardly to rest upon 35 said supporting feet of the uprights and being spaced from each other to provide a discharge opening, and downturned panels bent 40 from the outer edges of said shelf sections and constituting areas for the display of advertising matter.

3. A display stand comprising a pair of spaced end uprights, a pair of shelf members 45 disposed at substantially right angles to each other between said uprights, and each consisting of an inclined portion terminating at either end in a down-turned portion, said down-turned portions at the inner edges of 50 the shelf members being spaced apart to define with each other a discharge opening and said down-turned portions at the outer edges of said shelf members constituting exposed areas for the display of advertising.

In testimony whereof I affix my signature.

FRANCIS W. GIBSON.
